UNITED STATES PATENT OFFICE.

WILLIAM H. HASLET, OF PITTSBURG, PENNSYLVANIA.

CONCRETE RAILWAY-TIE.

984,912.

Specification of Letters Patent. Patented Feb. 21, 1911.

Application filed September 21, 1910. Serial No. 583,021.

To all whom it may concern:

Be it known that I, WILLIAM H. HASLET, a citizen of the United States, residing at Pittsburg, in the county of Allegheny and 5 State of Pennsylvania, have invented certain new and useful Improvements in Concrete Railway-Ties, of which the following is a specification.

My invention consists of an improvement 10 in railway ties of the class known as concrete reinforced.

The object of the invention is to provide a concrete tie having ample body portion, stiffening and reinforcing members so incorporated with it as to counteract the usual 15 service strains and also to prevent breakage or injury to the tie in handling, shipping, etc.

A further object is to provide a tie having 20 means for securing the rail in position whereby to avoid the use of securing bolts, screws, nuts or the like, and whereby the rail supporting and securing member is made in one piece and capable of being renewed or 25 replaced if necessary.

Other objects of the invention are to provide a cheap, serviceable tie which is practically indestructible, having the several foregoing features and together with others 30 as shall be more fully hereinafter described.

Referring to the drawings:—Figure 1 is a view of a complete tie in side elevation, partly broken away. Fig. 2 is a plan view of the tie. Fig. 3 is an end view, enlarged.

Fig. 4 is a similar cross sectional view on the line IV. IV. of Fig. 1. Fig. 5 is a perspective detail view showing the rail-supporting chair and its manner of mounting in the tie to engage it with the rail flanges.

Fig. 6 is a detail view of one of the bottom shoes. Fig. 7 is a similar view of the nut locking bearing plate. Fig. 8 is a similar view showing a modified form of bearing plate. Fig. 9 is a perspective detail view 45 of a shoe having attached fish plate extensions.

The interior stiffening frame of the tie consists of a longitudinally arranged rectangular truss having the upper and lower 50 chord members 2, 3, respectively, of plate metal, preferably steel, of suitable thickness and width to give ample stiffening effect to the surrounding concrete, with suf-

ficient body to provide against the tensional, torsional and compressional strains to which 55 the tie is subjected. Said upper and lower members 2, 3, are connected by vertical end members 4, 4, extending from one of said members 2 or 3 and connected with the other member by bolting or riveting or in any 60 other suitable manner, as indicated at 5. Any other construction or arrangement of the internal truss member may be adopted to secure the same results and I do not desire to be limited to the particular construction 65 as shown.

At positions in the tie corresponding to the positions of the rails when in place, are located the shoes 6. Said shoes are of rolled metal having downwardly bent flanges 7, 7, 70 along each side, parallel with the longitudinal center of the tie and at each end upwardly bent flanges or tongues 8, 8, somewhat narrower than the width of shoes 6, and extending sufficiently high to be bent 75 over upon the rail flanges, to secure them downwardly in position. Said shoes 6 are set immediately upon the upper chord member 2, the flanges 7 embracing its edges as shown, making snug engagement therewith 80 and fixedly locating each of said members with relation to each other.

Laid upon the top of shoe 6 lengthwise of it and engaging the tongues 8 by end recesses 9 and corner extensions 10, 10, is a 85 middle bearing plate 11, adapted to receive the rail.

At various points along the bottom of the tie I provide retaining bearing shoes 12 of plate metal bent upwardly at each end as at 90 13, embracing the sides of the tie as shown, said shoes being of any suitable number and location. Two of said shoes are located immediately below the rail bearing plates as shown.

For the purpose of securing all of the metal members of the tie fixedly together, I employ bolts 14 extending transversely from top to bottom. The bolt is provided with an annular abutment or extension 15, 100 15, at suitable points to bear downwardly and upwardly against the upper side of lower chord member 3, and under side of upper chord member 2 respectively, the bolt extending downwardly through said member and also through the lower shoe 12 and 105

having a securing nut 16. The bolt likewise extends upwardly through the upper chord member 2 and shoe 6 and is secured therein by a nut 17. Bearing plate 11 is provided with an opening 18 corresponding in outline to the nut 17, so that when said plate is laid upon the shoe 5 and engages nut 17 and is itself engaged between lugs 10 by the ears 8, said plate 11 will be fixedly held in place, and will also retain the nut 17 against rotation, thereby positively locking it.

In Fig. 8 a modified form of bearing plate 11' is shown having the middle bolt retaining opening 18' and the openings 9', 9', at each end for passage of the flanges or tongues 8. Said openings are closed by the ends of the plates as shown, thereby insuring positive engagement of the tongues at all sides. The additional bearing shoes 12, one or more at the middle portion of the tie between bolts 14 and one or more at the outermost portions thereof adjacent to the ends of the tie, are similarly held in place by bolts 19 which pass upwardly through the lower and upper chord members 3, 2, and are secured therein by terminal nuts or bolt heads 20 and also by nuts 21 underneath the shoes 12. By this means all of the bearing shoes, shown in detail in Fig. 5, are fixedly located in position and provide bearing surfaces for the tie while also protecting it from injury.

In Fig. 9 I show a modified construction of bearing shoe 6' having the flanges 7' while the tongues 8' which are bent up around the rail flanges are provided with fish plate extensions 23 having bolt holes 24 for connection with the rail webs in the usual way. By this construction the positive retention of the rails against longitudinal movement is further insured.

All of the metallic parts of the tie are embedded in and surrounded by the main body portion of concrete 22, as will be readily understood.

In manufacturing the tie, the metallic members are located in proper position within a suitable mold and the concrete is filled in around them and allowed to harden, whereupon the entire tie becomes a single complete unitary structure. The particular advantage of the bearing shoes 6 and their manner of incorporation in the tie is that in case of injury to the retaining ears 8 or if it is desired to replace the shoe for any other reason, it may readily be removed from the tie by merely chopping away the surrounding concrete, by removing plate 11 and nut 17, and replacing it with a new shoe, and then filling in the cavity with additional concrete and allowing it to harden.

The facility for attachment of the rail flanges by bending over the holding ears 8 obviates all difficulty as to loosening of nuts, etc., and the bending of said ears is quickly

and easily accomplished by first heating them by electric welding or other devices, and bending them down between suitable pressing clamps into engagement with the flanges.

It will be understood that the shoes 6 and their retaining flanges are of ample strength and weight and all of the parts should be in proportion to meet the various strains to which the tie is subjected.

The invention may be changed or varied in construction by the skilled mechanic in different details, but all such features are to be considered as within the scope of the following claims.

What I claim is:

1. A concrete tie provided with an internal reinforcing chord having upper and lower longitudinal members and end vertical connecting members, and bottom members embracing the tie at both sides and secured to said chord members by bolts, substantially as set forth.

2. A concrete tie provided with an internal reinforcing chord having upper and lower longitudinal members and end vertical connecting members, bottom members embracing the tie at both sides, upper rail-receiving and retaining members, and transverse securing bolts connecting all of said members, substantially as set forth.

3. The combination of a concrete body portion having longitudinally arranged stiffening members, rail receiving shoes having upwardly extending flange-engaging ears, and securing bolts extending downwardly through said shoes and through the longitudinal stiffening members and the bottom of the tie having terminal nuts substantially as set forth.

4. The combination of a concrete body portion having longitudinally arranged stiffening members, rail receiving shoes having upwardly extending flange-engaging ears, bottom bearing shoes, and securing bolts extending downwardly through said shoes and through the longitudinal stiffening members, substantially as set forth.

5. The combination of a concrete body portion having longitudinally arranged stiffening members, rail receiving shoes having upwardly extending flange-engaging ears, and securing bolts extending downwardly through said shoes and through the longitudinal stiffening members having fixed bearing abutments therefor, substantially as set forth.

6. The combination with the concrete body portion and internal reinforcing members, of a shoe embedded in the concrete having downwardly extending flanges embracing one of said reinforcing members and upwardly extending flange-securing ears, a bearing plate laid on said shoe between said ears having a nut engaging cavity, and a bolt secured to said reinforcing members

extending upwardly through said shoe and having a terminal nut in said cavity, substantially as set forth.

7. A rail bearing shoe having means for securing it to a tie, and upwardly extending flange engaging ears provided with fish plate extensions, substantially as set forth.

In testimony whereof I hereunto affix my signature in the presence of two witnesses.

WILLIAM H. HASLET.
